UNITED STATES PATENT OFFICE

ALFRED JOSEPH, OF ENGHEN, FRANCE, ASSIGNOR TO COMPAGNIE INTERNATIONALE
POUR LA FABRICATION DES ESSENCES ET PETROLES, OF PARIS, FRANCE, A LIMITED
JOINT-STOCK COMPANY OF FRANCE

REGENERATION OF CATALYSTS

No Drawing. Application filed July 11, 1929, Serial No. 377,623, and in France July 13, 1928.

This invention relates to a method of regenerating catalyzing agents in the treatment of carbonaceous substances or heavy hydrocarbons for the conversion thereof into light hydrocarbons.

Catalyzing agents such as metals, metallic oxides, mixtures of metals or alloys, are usually employed for promoting reactions, and particularly for causing the fixation of hydrogen on hydrocarbon gases, derived either from the distillation of combustibles (lignites, shales, peats and the like) or from the distillation or cracking of tars, heavy oils or other similar starting materials. Such catalyzing agents, at the end of a more or less long period, variable according to their nature and the nature of the starting materials, become coated and sulphided, particularly in cracking operations wherein they become entirely charged with sulphur and carbon. It then becomes imperative to proceed with the regeneration thereof.

For this purpose, various means tending generally to eliminate the sulphur either by the action of hydrogen or of a gas containing hydrogen, or by the action of a stream of air, and to eliminate the carbon by the action of a stream of air or oxygen giving rise to the formation of carbon dioxide or carbon monoxide or a mixture of these gases, have been proposed.

The subject of the present invention is a method of regeneration which enables these known means to be utilized in a far more effective manner. This method consists, in principle, in bringing into contact with the contaminated catalysts, a mixture of air or oxygen and steam, by admitting such mixture, by a nozzle into the reaction chamber containing the catalyst to be regenerated. The dissociation of the steam gives rise to the formation of nascent oxygen and hydrogen. The oxygen thus set free adds itself to that of the injected air for aiding the latter to burn the carbon and sulphur, and produce, according to temperature, CO or CO₂, or a mixture of these two gases and a slight amount of SO₂. The air is injected in a suitably regulated amount for ensuring progressive combustion.

As regards the nascent hydrogen, this reduces the formed SO₂ to the state of H₂S, and likewise reduces the metallic sulphide, beyond the initial zone where the combustion of the carbon has just been produced. Subsequently, when the oxygen has been brought to act beyond the initial zone, it will find itself only in the presence of a very slight quantity of sulphur. It has been determined that at the outlet end of the apparatus there issues practically as a sulphur compound, only H₂S. By this, the oxygen is therefore in the major part employed in the combustion of carbon, and not in the combustion of the sulphur, which presents the important advantage of rendering impossible the formation of sulphates, in thus enabling a complete regeneration of the catalyzing agents.

The employment alone of steam or of air, which means have already been practiced, would be unadapted to furnish the same results.

By the employment of steam alone the desired amount of oxygen is not furnished to effect, by the combustion of the carbon, the elevation of temperature necessary for the dissociation of the steam; a considerable addition of heat is required, which represents a serious expense which the new method avoids. By employment of air alone, such addition of heat is avoided, but, on the other hand, the reverse disadvantage is encountered of an excessive generation of heat, prejudicial to the preservation of the catalyzing agents.

In carrying out regeneration in accordance with the invention, two or more catalytic reaction chambers may be mounted in parallel, one being in service when, in the other or others, cut out of circuit, regeneration is being effected by a mixture of steam and air or oxygen, and vice versa. The alterations of placing in circuit for the operative reactions and out of circuit with a view to regeneration may be effected by employing an arrangement for cyclic permutation which forms the subject of French Patent No. 654242, filed the 6th October, 1927.

As a modification, to the gases on the ad-

mission thereof into the reaction chambers, may be added the mixture in suitable proportions of steam and air or oxygen, the regeneration being effected in such case immediately after the reaction and without putting the reaction chambers periodically out of circuit.

Claims:

1. The method of regenerating catalysts used in the treatment of carbonaceous substances which consists of removing the carbon and sulphur impurities by subjecting the contaminated catalyst to the simultaneous action of steam and air.
2. The method of regenerating catalysts used in the treatment of carbonaceous substances which consists in removing the carbon and sulphur impurities by subjecting the catalyst to a mixture of steam and oxygen.
3. The method of regenerating catalysts used in the treatment of carbonaceous substances which consists in removing the carbon and sulphur impurities by subjecting the catalyst to a stream of steam enriched with air.
4. The method of regenerating catalysts used in the conversion of heavy hydrocarbons into light hydrocarbons which consists in the removal of carbon and sulphur by subjecting the catalyst to the simultaneous action of oxygen and steam, the supply of oxygen being controlled to prevent the development of excessive temperatures and reduction of the catalyst.
5. The method of regenerating catalysts which consists in removing the carbon and sulphur impurities therefrom by injecting, through a nozzle, into the chamber containing the contaminated catalyst a gaseous mixture containing steam and oxygen.

In testimony whereof I have signed this specification.

ALFRED JOSEPH.
